(57) **CLAIM**

The ornamental design for a protective case for electronic product, as shown and described.

DESCRIPTION

FIG. 1 is a front view of a protective case for electronic product of the present invention when the case is in a closed configuration.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a flatten expanded view of the interior of the protective case for electronic product of the present invention.

FIG. 8 is a perspective view of the protective case for electronic product of the present invention when the protective case is in a configuration to support a tilted view of a flat screen electronic device; and,

FIG. 9 is another perspective view of the protective case for electronic product of the present invention when the protective case is in a configuration to support a tilted view of a flat screen electronic device.

The broken line showing in the drawings is for illustrating purpose only and does not form part of the claimed design.
